AUTOMATIC PIN SETTER FOR BOWLING ALLEYS

Albert R. Bentz, Toledo, Ohio, assignor to Singer Manufacturing Company, Toledo, Ohio, a corporation of Ohio

Application July 17, 1933, Serial No. 680,676

10 Claims. (Cl. 273—43)

This invention relates to a pin setter for bowling alleys which may be controlled, as desired, from the front end of the alley to sweep the alley clean, to reset the pins, and to return 5 the balls.

The invention, in its preferred form, comprises a sweeper of improved construction and means for actuating the same, a set of distributor tubes which are adapted to hold three sets of pins, a 10 table adapted to receive the first set or any selected portion thereof, and to set the same while the other pins are held in reserve in the distributor tubes, means in the pit for separating the pins from the balls and delivering the pins to the various distributor tubes while the balls are returned to the front end of the alley, means to indicate whether each individual pin is properly set, and a control board provided with push buttons controlling these different instrumentalities.

20 The above and other features of the invention will be more particularly described in connection with the accompanying drawings, in which—

Fig. I is a side elevation of the rear end of the alley, together with the pin elevator and the index tubes which receive the pins therefrom;

Fig. II is a front elevation of the pit and the pin elevator;

Fig. III is a plan view of the rear end of the alley and the ball elevator;

30 Fig. IV is a side elevation of the parts shown in Fig. III;

Fig. V is a section taken on the line 5—5 of Fig. III;

Fig. VI is an enlarged side elevation of the ball elevator;

Fig. VII is a plan view of the ball elevator;

Fig. VIII is a side elevation of the upper portion of the pin elevator and the means for transferring the pins to the index tubes;

40 Fig. IX is a front elevation of the parts shown in Fig. VIII;

Fig. X is a side elevation of one of the index tubes and the means for delivering the pin thereto, the elevator being shown in a different position than is shown in Fig. VIII;

Fig. XI is a front elevation of an index tube and the means for delivering a pin thereto;

50 Figs. XII, XIII and XIV illustrate in front elevation successive positions of a distributor tube and the means for delivering a pin from an index tube thereto;

Fig. XV is a side elevation of the distributor tubes and the rack or table for setting the pins;

Fig. XVI is a bottom plan view of the rack or table for setting the pins;

Fig. XVII is a section taken on the line 17—17 of Fig. XVI;

Fig. XVIII is a view similar to Fig. XVII, but showing the parts in a different position;

Fig. XIX is a side elevation of the sweeper and table and the mechanism for operating the same;

Fig. XX is a detail view of the catch for holding the sweeper;

Fig. XXI is a plan view of the sweeper and table operating mechanism;

Fig. XXII is a diagram of the wiring for controlling the various instrumentalities;

Fig. XXIII is a front elevation of the control board;

Fig. XXIV is a vertical section of one of the spots and illustrates in connection therewith the means for indicating when the pin is properly spotted.

Fig. XXV is a front elevation of the gearing for driving the various instrumentalities.

As illustrated in the drawings, the invention is associated with the rear end of a bowling alley 1, having side rails 2, and a pit 3 provided at its rear side with a bumper 4. Within the pit 3 and spaced above the bottom thereof is a camel back 5 with its edges far enough from the sides of the pit to allow the pins to pass downwardly into the bottom of the pit. The balls 6, however, as they pass into the pit, roll along the edges of the camel back and through one of the openings 7 in the bumper. Tracks 8 in rear of the bumper guide the balls through an opening 9 into the bottom of an elevator well 10. In the bottom of the elevator well 10, there is an annular seat 11 on which each successive ball rests until it is lifted by the ball elevator.

The ball elevator comprises a sprocket chain 13, which travels about sprockets on the shafts 14 and 15, as indicated by the arrow in Fig. VI. Vanes 16 project laterally from the chain 13 and are supported in such position by arms 17. The side of the elevator well 10 is provided with a slot 12 through which the vanes 16 pass during their upward travel. Whenever a ball comes to rest upon the seat 11, the next vane 16 carries it upwardly within the well 10. The vane is disposed with a lateral slope which guides the ball away from the entrance opening 9 and, as the ball reaches the upper end of the well, delivers it laterally into a race way 18 along which the ball rolls to the front end of the alley.

The pin conveyor or elevator comprises a succession of cups 19, each of which is secured to the end of an arm 20 pivotally supported upon a pin 21, which transversely connects a pair of sprocket

chains 22. Each chain 22 travels about an upper sprocket 23, which is secured to a shaft 24, thence downwardly about an idler 25, thence forwardly about an idler 26, thence rearwardly about a sprocket 27 which is secured to a shaft 28, and thence upwardly to the sprocket 23 at the upper end of the elevator.

The pin elevator shaft 24 is driven by an electric motor 29 through a gear box 30 and sprocket gearing 31. The ball elevator shaft 15 is driven from the shaft 28 by sprocket gearing 32.

In order to hold the pin cup 19 in proper projected position while it carries the pin, and to allow the pin to be released as it reaches the upper end of the elevator, the arm 20 extends inwardly beyond its pivot and is provided with a cross head 33 carrying rollers 34 and 35, which are guided between cam tracks 36 and 37. The track 37 is provided with an offset 38 at the upper end of the elevator, as shown in Figs. VIII and X, so that when the pin reaches this point, the cup 19 is permitted to tilt downwardly to allow the pin 39 to slide therefrom. At the same time, the neck of the pin is engaged by the curved end 40 of an arm 41, which is secured to the upper side of a hopper 42. There are two arms 41, one at each side of the hopper to insure contact with the pin whether the head of the pin projects to the right or to the left from the cup 19. As the pin is thus guided into the hopper 42, its neck engages a notch 43 at the upper end of the hopper and causes the pin to be guided butt first into the hopper.

As shown in Figs. X and XI, a tongue 44 is secured to a pin 45 mounted at the side of the hopper 42 and normally projects into the hopper far enough to engage the thickest portion of the pin and detain it until the tongue is retracted. The pin 45 is pivotally mounted and an arm 46 secured thereto is yieldingly held by a spring 47 in position to retain the pin 39 within the hopper. An arm 49 projects downwardly from the tongue 44 and is adapted to be engaged by a trip, as hereinafter described, at the proper time to release the pin from the hopper.

A series of index tubes 50 are mounted upon a revolving support 51 which is driven from the shaft 24, so that they are carried successively beneath the hopper 42. Each index tube carries a cam 52, as shown in Figs. X and XI, which engages a roller 53 on the lower end of the arm 49 to retract the tongue 44 and release any pin which may be held within the hopper 42.

Each index tube 50 also has a retaining tongue 54 mounted on the side thereof and normally projecting inwardly to a position to engage the pin as it is delivered to the index tube. Each tongue 54 is secured to a pivot pin 55 from which a finger 56 hangs downwardly. A set of ten distributor tubes 57 are arranged beneath the path of the index tubes in proper position to distribute the pins to the rack or table by which they are to be set. Each distributor tube 57 is of sufficient length to hold three pins. A trip arm 58 is pivotally mounted at 59 on the tube 57 and is normally in the position shown in Fig. XII, so that it will engage a roller 60 on the end of the arm 56 and release a pin 39 from the first index tube 50 which contains one.

70 A solenoid 61 is carried by each tube 57 in such a position as to pull the trip arm 58 downwardly out of the path of the roller 60 whenever the solenoid is energized. Current is supplied to the solenoid 61 through a switch 62, which is controlled by a spring arm 63 within the tube 57.

Whenever the tube is full, the uppermost pin engages the spring arm 63 to close the switch 62, thus energizing the solenoid, so that the trip arm 58 will be held in inoperative position and the index tube will pass by without releasing any pin which may be contained therein.

In order to insure an adequate supply of pins to all of the distributor tubes at all times, it is desirable to supply the machine with several more pins than are usually required. With such a surplus supply, it may of course happen that at some time, when all of the distributor tubes 57 are full, an index tube containing a surplus pin may pass over them. In order to prevent such surplus pin from being carried beneath the hopper 42 and possibly interfering with another pin being delivered from the hopper, a false tube 57a is arranged to receive any pin which is carried by an index tube past the ten distributor tubes, and to return it to the pit. This positively prevents the surplus pins from interfering with the hopper delivery.

The pins in each distributor tube 57 are normally retained therein by a spring held finger 63a which is adapted to be retracted to release the pin by means of a solenoid 63b located adjacent the lower end of the tube, whenever the respective solenoid is energized. These solenoids are wired so that they may be energized separately or all energized simultaneously.

The pins are set up by a rack or table 64 to which they are delivered from the distributor tubes 57. This rack or table is supported by a frame 65 which has racks 66 on the side rails thereof, these racks being in engagement with gears 67. Each gear 67 is secured to a shaft 68 on which is secured a bevel gear 69. The gear 69 is in mesh with a bevel gear 70 secured to a shaft 71, the latter being adapted to be driven in one direction to lower the table and in the other direction to raise the same.

For controlling the movement of the shaft 71, a clutch member 72 is splined thereon and is adapted to be shifted into engagement with a bevel gear 73, which is constantly rotated in a direction to lower the table. An opposed clutch member 74 is splined on the shaft 71 and is adapted to be moved into engagement with a constantly rotating bevel gear 76 to raise the table. The bevel gears 73 and 76 are driven from opposite sides of a bevel gear 77 which is secured to one end of a transverse shaft 78. A bevel gear 79 is secured to the opposite end of the shaft 78 and is driven by a bevel gear 80 secured to the lower end of a shaft 81. A bevel gear 82 secured to the upper end of shaft 81 is driven by a bevel gear 83 secured to a drive shaft 84, which is operatively connected to the motor 28.

The table 64 has a set of leaves 85 which are respectively opposed to a set of leaves 86, each pair of leaves 85 and 86 being adapted to support and set one row of pins. The pins, as they are released from the distributor tubes, are guided by the respective deflectors 87 into proper position between the leaves so that when they are released from the latter they will be properly spotted. Each pin, as it lodges against the table, supports the pin above it until the latter is engaged and held by a retaining arm 88. The leaves 85 are controlled and operated in unison through the medium of links 88, while the leaves 86 are similarly controlled by links 89. The rearmost link 88 is connected to one end of a lever 90, which is intermediately pivoted at 91, and the rearmost link 89 is connected to the opposite end 75

of the lever. A vertically yieldable stud 92 extends downwardly from the table and normally engages the lever 90, as shown in Figs. XVI and XVII, to hold the leaves 85 and 86 in pin supporting position. As the table is lowered, however, to pin setting position, the stud 92 engages an abutment 93 and is moved upwardly, releasing the lever 90 and permitting it to move forwardly to a position shown in Fig. XVIII, which is sufficient to release the pins. This movement is facilitated by springs 93^a connecting the leaves. As the table is again raised, a bar 94 projects through a slot 95 in the table and its inclined surface 96 engages the lever 90, returning it to its former position with the leaves 85 and 86 closed. A spring 97 on the stud 92 returns the stud to its initial position.

The sweeper 98 comprises a bar which is provided with rollers 99 adapted to engage the surface of the alley during its sweeping movement and has arms 100 which have a telescoping connection with sleeves 101, the telescoping movement being limited by a pin and slot connection 102. The sleeves 101 are secured to the ends of a shaft 103 on which is splined a clutch member 104. A companion clutch member 105 is secured to a bevel gear 106 which is mounted on the shaft 103 and is adapted to drive the sweeper during its sweeping movement. An opposed companion clutch member 107 is secured to a bevel gear 108 and is adapted to drive the sweeper during its retractive movement.

The bevel gear 106 is constantly driven by a bevel gear 109 which is secured to the lower end of a vertical shaft 110, the latter having a bevel gear 111 secured to its upper end which is driven by the bevel gear 79 secured to the shaft 78. The bevel gear 108 is constantly driven by a bevel gear 113 which is secured to the lower end of a vertical shaft 114, the latter having a bevel gear 115 secured to its upper end and driven by the bevel gear 77 secured to the shaft 78.

For controlling the sweeper clutch member 104, a shaft 117, driven by the shaft 84, has a bevel gear 118 secured thereto which drives a bevel gear 119 secured to the upper end of a vertical shaft 120. A bevel gear 121, secured to the lower end of shaft 120, drives a bevel gear 122, which is adapted to drive a cam shaft 123 through the medium of a clutch 124. A cam 125 on the shaft 123 controls the movement of a shifting lever 126, which shifts the clutch member 104 in proper sequence to effect the successive movements of the sweeper 98.

The clutch 124 is controlled by a lever 127 which is actuated by the energization of a solenoid 128 to move the clutch into engagement. Upon engagement of the clutch, the shaft 123 rotates through one complete revolution, whereupon a pin 129 on the clutch engages an inclined cam surface 130 and disengages the clutch. During this rotation of the shaft 123, the sweeper clutch member 104 is shifted by the lever 126, actuated by the cam 125, first to move the sweeper over the table to remove therefrom all pins left standing and all dead wood, and then to return the sweeper to its position of repose, where it is held by the flat spring 131, as shown in Fig. XX. At the completion of this operation, the lever 126 is actuated to shift the clutch member 104 to neutral position.

As the sweeper 98 concludes its sweeping movement, an arm 132 secured to the shaft 103 engages and closes a switch 133, which closes a circuit through a solenoid 134. The solenoid 134,

thus energized, attracts its armature 135 which is secured to a yoke 136 controlling the positions of the clutch members 72 and 74. As the armature 135 is moved toward the solenoid 134, therefore, the clutch member 72 is moved into operative engagement with its companion member to drive the shaft 68 in a direction to lower the table. During the downward movement of the table, an arm 137, carried thereby, opens the switch 133, deenergizing the solenoid 134. As the table approaches its lowermost position, a cam 138 engages an arm 139 of the yoke 136, opening the clutch 72. At the same time a lug 140 closes a switch 141, thus closing a circuit through a solenoid 142. This attracts the armature 143 which is carried by the yoke 136 and causes the yoke to shift clutch member 74 into engagement, thereby rotating the shafts 68 in a direction to raise the table to its initial position. During the upward movement of the table, a lug 144 opens the switch 141 and, as the table reaches its initial position, a finger 145 engages a cam surface 146 on the yoke arm 139 to release the clutch member 74, stopping the movement of the table. The table is counterweighted so that it will remain in its initial position until the solenoid 134 is again energized.

Referring now to Figs. XXII, XXIII and XXIV, it will be noted that each pin spot is formed with an outer metallic sleeve 147 and an inner core 148 insulated therefrom. The pin 39 has a metallic base 149 which connects the sleeve 147 to the core 148, if the pin is properly spotted. This closes a circuit from the service wires 150 and 151 through wires 152 and 153 to an electric lamp 154 on the panel 155, each lamp 154 being located in a position corresponding to the respective pin. Thus, by glancing at the panel, it may be positively ascertained whether the pins are properly set.

Associated with each lamp 154, is a push button 156 corresponding to the particular solenoid 63^b which releases a pin for the spot corresponding to that push button. Whenever a button 156 is pushed, a circuit is closed from service wire 150 through wire 157, button 156, wire 158 and solenoid 63^b to the service wire 151. Thus it will be seen that any desired selection of individual pins may be spotted.

If a full set of pins is desired, the button 159 is pushed and that closes a circuit through wire 160 and all of the wires 158 to energize all of the solenoids 63^b simultaneously.

After the pins to be set have been released into the table 64, the sweeper and table actuating button 161 is pushed. This first closes a circuit through wire 162 and solenoid 128 to start the rotation of the shaft 123. This initiates a succession of operations, as above described, which includes the operation of the sweeper 98, the closure of the switch 133, which closes a circuit through wire 163 and solenoid 134, and the closure of switch 141, which closes a circuit through wire 164 and solenoid 142.

A switch 164 is also located on the panel 155 and is adapted to close a circuit through wire 165 to the motor 29.

In order to insure the most satisfactory operation of the pin setter, it should be supplied with thirty pins, or nearly that number, so that each distributor tube 57 will contain at least one pin whenever a solenoid 63^b is energized to release a pin therefrom. At the beginning of each frame, the button 159 is pushed, causing a full set of pins to be delivered to the table 64, which is then 75

automatically actuated to spot the pins, after the alley has been cleared from the previous frame. After the first ball is rolled, if some of the pins are left standing, this will be indicated by the 5 lamps 154 which remain lighted in the panel 155. If there is also dead wood on the alley, the buttons beneath the lighted lamps are pushed. This sweeps the alley clean and resets only such pins as were not knocked down by the first ball. If 10 there is no dead wood, it is of course unnecessary to reset any pins until a new frame is set up.

From the foregoing description, it will be seen 15 that my automatic pin setter may be controlled from the front end of the alley by electrical means to perform all of the essential operations 20 which are usually performed by alley toys. Although I have shown and described its specific construction in detail, it will be apparent that the same may be modified to a considerable extent without departing from the scope of the appended claims.

What I claim is:

1. The combination with a bowling alley having a pit at the rear end thereof, of a crowned member spaced above the bottom of the pit with its edges spaced from the sides of the pit a distance greater than the largest diameter of the pins but less than the diameter of the balls, whereby the balls are separated from the pins in the pit, means for returning the balls to the front of the 25 alley, and means for elevating the pins and distributing them in position for resetting.
2. The combination with a bowling alley having a pit at the rear end thereof, of a crowned member spaced above the bottom of the pit with its edges spaced from the sides of the pit a distance greater than the largest diameter of the pins but less than the diameter of the balls, whereby the 30 balls are separated from the pins in the pit, a return ball raceway, a continuously operating endless ball elevator, means for delivering the balls from the pit to said elevator, means for delivering the balls from the elevator to said raceway, and means for elevating the pins and distributing them for resetting.
3. The combination with a bowling alley having a pit at the rear end thereof, of a crowned member spaced above the bottom of the pit with its edges spaced from the sides of the pit a distance greater than the largest diameter of the pins but less than the diameter of the balls, whereby the 35 balls are separated from the pins in the pit, means for returning the balls to the front of the alley, pin distributing and setting mechanism, and means including a continuously operating pin conveyor and elevator to transfer the pins from the pit to the pin distributing mechanism.
4. In a pin setting apparatus for bowling alleys, a pin setting table, means for supporting pins in said table in proper relative position for setting, a set of distributor tubes above the table, means 40 for delivering pins butt first to said tubes, means

for delivering any predetermined selection of pins from the respective distributor tubes to the table, and means for setting the pins which are thus delivered to the table.

5. In a pin setting apparatus for bowling alleys, 5 a pin setting table, a set of distributor tubes above said table, each adapted to hold a plurality of pins, a set of index tubes movable successively over the upper ends of said distributor tubes, means for delivering pins to said index tubes, and a trip for 10 each distributor tube operable, only when the tube is not full, to deliver a pin thereto from the next index tube containing one.

6. The combination with a bowling alley having a pit, of a pin setting table, a set of distributor tubes above the table, a set of index tubes movable successively over the upper ends of the distributor tubes, means for delivering pins to said index tubes and thence to the distributor tubes, and means for returning to the pit any pin 20 which may be contained in an index tube after the distributor tubes are full.

7. In a pin setting apparatus for bowling alleys, 25 a hopper, means for delivering pins butt first one by one to said hopper, a set of index tubes movable successively beneath the hopper, means for retaining each pin temporarily in the hopper, means to release the pin from said retaining means and deliver it to the next index tube, a set of distributor tubes beneath the path of the index 30 tubes, each adapted to hold a plurality of pins, and means, operable only when a distributor tube is not full, to deliver a pin thereto from the next index tube containing one.

8. In a pin setting apparatus for bowling alleys, 35 a hopper, means to deliver pins to said hopper, a set of index tubes movable continuously beneath said hopper, means to retain each pin temporarily in said hopper, means carried by said index tubes to release said pin retaining means, a set 40 of distributor tubes adapted to hold a plurality of pins, and means to deliver a pin from the first of said index tubes containing one to the first of said distributor tubes which is not full.

9. The combination with a bowling alley having a pit, of a pin setting table including oppositely disposed leaves, means for delivering pins to said table in vertical position, said means including a set of distributor tubes above the table adapted to hold a plurality of pins, a set of index 50 tubes movable continuously over said distributor tubes, means to deliver pins from said index tubes to said distributor tubes, and means for returning to the pit any pin which may be contained in an index tube after the distributor tubes are full. 55

10. In a pin setting apparatus, for bowling alleys, a pin setting table, a set of distributor tubes above the table, means to deliver pins to said tubes, and means to deliver any predetermined selection of pins from said tubes to said table.

ALBERT R. BENTZ.
